UNITED STATES PATENT OFFICE.

VICTOR A. HARDER, OF NEW YORK, N. Y., ASSIGNOR TO THE MAYOR, LANE
& COMPANY BRASS WORKS, OF SAME PLACE.

BATHING APPARATUS.

SPECIFICATION forming part of Letters Patent No. 324,686, dated August 18, 1885.

Application filed November 7, 1884. (No model.)

To all whom it may concern:

Be it known that I, VICTOR A. HARDER, of New York city, in the county of New York and State of New York, have invented certain new and useful Improvements in Bathing Apparatus; and I do hereby declare that the following is a full, clear, and exact description thereof, reference being had to the accompanying drawings, making part of this application.

My invention relates to certain improvements in bathing apparatuses, which will be hereinafter more fully explained, and particularly specified in the claims.

In the accompanying drawings, Figure 1 is a front view of a portable bathing apparatus embodying my invention, with the front portion of the cabinet removed. Fig. 2 is a vertical central section of the same at *x x*, with the front of the cabinet added and looking toward the left. Fig. 3 is a horizontal section on line *y y* of Fig. 1.

In the several views the same parts will be found designated by the same letters of reference.

The apparatus shown in the drawings, forming part of this application and about to be described, comprises in its structure several different kinds of bathing appliances, to the combined use of all of which I do not wish my invention considered as limited, for any one or more of such various appliances may be used without others and yet involves some one or more of the various improvements devised by me.

The apparatus illustrated contains provision for a "needle-spray" bath, either hot or cold, a shower-bath, either hot or cold, a descending douche, an ascending douche, and what are known as "liver-sprays," as well as provision for a vapor bath.

A is a standard, the base of which is secured, preferably by screws, to the floor of the cabinet, if one be used, or to the floor of a room or apartment in case the apparatus be fitted up in the latter, and this standard serves to assist in supporting the needle-spray water-supply pipes, &c.

B B' B² B³ are four curved needle-spray pipes arranged on each side of the apparatus, one over the other, at about equal distances apart. The outer ends of these pipes are

closed, and are fastened by flanges or plates *b* to the sides of the cabinet, (where one is used,) and, running around in about quarter-circles, their inner ends are connected to four cross *T*-couplings, *C C' C² C³*, which latter have their vertical water-ways connected by short sections of pipe *1 2 3 4 5*, the uppermost one, *1*, of which is connected to a *T*-coupling, *a*, from the horizontal arms of which extend pipes *6 7*, that are connected by elbow-couplings *b' b'* to vertically-extending pipes *8 9*, at the lower portions of which are respectively faucets *D D'*.

The lower end of the pipe *8* is connected to a horizontally-arranged pipe-section, *10*, with a water-way that extends only from the cross *T*-coupling *C⁴* to the lower end of the pipe *8*, the other or right-hand side of the pipe-section *10* being closed and connected with one horizontal arm of another cross *T*-coupling, *C⁵*, situated at about the center of the apparatus and between tiers 2 and 3 of the needle-spray pipes. This coupling *C⁵* has, however, only a vertical water-way, and its right-hand horizontal branch is connected to still another cross *T*-coupling, *C⁶*, which also has a vertical water-way only, and that in turn is connected to another cross *T*-coupling, *C⁷*.

The lower end of the pipe *9* is connected to the cross *T*-coupling *C⁶* at its upper arm, and to the lower arm of this coupling is connected a vertical elbow-pipe, *E*, that is connected to a horizontally-arranged elbow, *E'*, in rear of the elbow *E*, from which elbow *E'* extends a horizontal pipe, *E²*, that connects with a *T*-coupling, *E'*, that joins hot-water-supply pipe *E⁴*. This last-mentioned pipe preferably enters the cabinet at its lowermost portion, and extends upwardly after joining the pipe *E²* past the same and near to a level with the uppermost tier of the needle-spray pipes, but in rear of the series, then turns horizontally by means of an elbow-coupling, *E⁵*, and by means of another elbow, *E⁶*, and a *T*-coupling, *E'*, connects with a vertically-arranged pipe, *F*, that by means of suitable couplings and pipes, *F' F² F³ F⁴ F⁵*, connects with a shower-bath device, *G*, suspended from the upper portion of the cabinet, and about centrally thereof.

The horizontal portion of the hot-water-supply pipe *E⁴*, that lies between the elbows *E⁵*

and E⁶, is provided, at about its middle, with a faucet, E⁸, the stem of which is prolonged and projects outwardly beyond the pipe 2, so that the handle part of the faucet may be conveniently grasped and turned.

The couplings C⁴ and C⁷ are each provided at their outer ends with an elbow connecting-section, H, that is provided with a faucet, H', in a pipe, H², that leads to the liver-spray device H³, which is perforated throughout its face, so as to throw the water toward the center of the cabinet.

The cold-water pipes J K also preferably enter at the lower portion of the cabinet from its rear, and on each side of the center thereof, as seen. The pipe J extends upwardly and connects with the lower vertical branch of the cross T-coupling C⁴, from the upper vertical branch of which extends a pipe-section, J², 15 that is provided with a faucet, J³, and this pipe, by means of couplings and other connecting-pipes J⁴, J⁵, J⁶, J⁷, J⁸, J⁹, J¹⁰, J¹¹, J¹², J¹³, 20 J¹⁴, and J¹⁵, connects with the douche-nozzle situated about centrally of the shower-bath 25 device G.

The pipe K extends upwardly to a T-coupling, K', from which extends a vertical pipe, K², that connects with the lower branch of the cross T-coupling C⁷, from the upper vertical 30 branch of which runs another piece of pipe, K³, (in which is arranged a faucet, K⁴), that connects with the T-coupling E⁷.

From the T-coupling K' extends a branch pipe, L', that runs downwardly, then inwardly to about the center of the cabinet, and which is provided at this point with an upwardly-extending nozzle, L², to give what is known as an "ascending douche." At a suitable point in this branch pipe L' there is arranged a faucet, L³, for controlling the supply.

The foregoing description of the construction of a bathing apparatus embodying my invention, taken in connection with the following description of the mode of operation of the same, will enable any one skilled in the art to which my invention relates to make and use an apparatus embodying my several improvements.

Suppose, now, the apparatus to have been 50 properly connected with the cold and hot water supply service-pipes of the house, and the water admitted through the pipes E⁴, J, and K: it will rise in the first-mentioned pipe and its connections up to the faucets D' and E⁸, 55 which are supposed now to be closed, and the water rising in the cold-water pipes J and K fills those pipes and their connections as far as the faucets D' H' J³ K⁴ L³, which also are now supposed to be in a closed condition.

60 If it be desired now to take a needle-spray bath with cold water, the faucet D is turned to open the way, and the water rises through the pipe 8 and its connections, and down into the coupling C, out through its lateral branches around the pipes B, down through the pipe 2 into the coupling C', out into the pipes B',

down through the coupling C⁶ into the coupling C², out into the pipes B², and down through the pipe 5 into the coupling C³, and laterally out into the pipes B³, which pipes B 70 B' B² B³, being perforated with fine apertures, will all simultaneously, or nearly so, emit needle-like sprays directed toward the center of the compartment, at about which the bather is supposed to be located.

If it be desired now to take a hot-water needle bath, the faucet D is turned off or back to its first position, and the faucet D' is opened to permit the hot water to rise through the pipe 9 and its connections and down into 80 the cross T-couplings C C' C² C³ and the needle-spray pipes B B' B² B³, in the manner just before alluded to.

If it be desired to take a liver-spray bath, the faucets H' H' are turned on, and the cold water will run from the pipes J and K out through the liver-spray devices and be directed 85 against the sides of the bather.

If it be desired to take a cold shower-bath, the faucet K⁴ is turned, and the water ascends 90 through the pipes and couplings F' F' F² F³ F⁴, &c., to the shower-giving device G, from which it descends.

If it be desired now to take a hot shower-bath, the cold water is turned off, and the faucet E⁸ is opened, allowing the water to run through the horizontal pipe into the pipe F, and up through its connections to the shower-giving device G.

If it be desired to use the descending douche, 100 the faucet J³ is turned so as to open the way, and the water rises through the pipe J⁴ and its connections to the douche-nozzle, from which a jet is thrown down on the bather.

If it be desired to use the ascending douche, 105 the faucet L³ is turned, and the water from the pipe K permitted to first descend through the pipe L' and then ascend from out the nozzle L².

It will be observed that by operating the 110 proper faucets needle-spray and shower baths of mixed cold and tepid water may be taken, and the temperature of the water thus regulated to suit the requirements or wishes of the bather; and, furthermore, that by the arrangement of the supply-pipes to the different devices for giving the various baths all the means for controlling the supplies of water are grouped together within easy reach of the bather, and that by their proper manipulation from his position at the center of the apparatus the bather may take any one kind of bath or take simultaneously baths of two or more different kinds.

Where the cabinet is used, as in the case illustrated, it is, of course, supposed to be lined with zinc or other material, and to be provided with an aperture or pipe at the bottom to carry off the waste or bathing water.

It will be understood, of course, that in lieu 130 of using the cabinet the apparatus may be set up in a room or apartment of a house and

operated in the manner described. Where a cabinet is used, in addition to the water baths so far explained, vapor baths may be given by making a connection outside the cabinet, at, 5 say, the point M, with a nozzle that extends through the cabinet or box N, and has some suitable vapor-generator located externally. Of course, in the use of the vapor bath, the door n and window n' of the cabinet will have 10 to be closed, while such would not be the case when water baths are being taken.

It will be understood, of course, that where the cabinet is not used some modifications as to details of construction will be necessary.

15 I have built some of these apparatuses to be set in the corners of rooms, and where this has been done modifications in detail have of course been made.

Having so fully described my invention 20 that those skilled in the art can make and use machines embodying the same, what I claim as new, and desire to secure by Letters Patent, is—

1. The combined arrangement of the series 25 of needle-spray pipes, suitably connected together by couplings and communicating with the hot and cold water supply pipes, the liver-spray devices H³ H³, suitably connected with the sources of water-supply, as described, the 30 shower-giving device G, suitably connected with the hot and cold water supply pipes, and the ascending-douche nozzle L² and its water-supply connections, together with a series of faucets for controlling the supply of water in 35 the respective devices above mentioned, all in substantially the manner and for the purposes hereinbefore set forth.

2. The combination, with the liver-spray devices H³ H³, suitably connected with the sources

of water-supply, as described, of the shower-giving device G, suitably connected with the hot and cold water supply pipes, the ascending-douche nozzle and its water-supply connections, and the descending-douche nozzle and its connections, and a series of faucets for 40 controlling, respectively, the different above-mentioned water-ejecting devices, and arranged within convenient proximity to the person using the bathing apparatus, all substantially as and for the purposes set forth. 45

3. The series of horizontally-disposed needle-spray pipes B B' B² B³, suitably connected together by couplings C C' C² C³, and intermediate pipe sections, 2, 3, 4, and 5, in combination with the cold-water-supply pipe J and its 50 connections, the hot-water-supply pipe E⁴ and its connections, and cocks D D', for controlling the supplies. 55

4. In combination with the horizontally-disposed needle-spray pipes and connections, 60 the cold-water-supply pipe K, the hot-water-supply pipe E⁴, the shower-giving device G, the intermediate connections, and the cocks K⁴ and E⁸, for controlling the supplies, all as set forth. 65

5. In combination with the horizontally-disposed needle-spray pipes B B' B² B³ and their shown and described supply-pipes and connections, the pipes J and K, the liver-spray devices H³ H³, the intermediate connections, 70 and the cocks H' H', for controlling the supplies, all substantially as set forth.

In testimony whereof I have hereunto set my hand this 29th day of October, 1884.

VICTOR A. HARDER.

In presence of—

JACOB FELBEL,
PH. SCHMIDT.
